UNITED STATES PATENT OFFICE.

GEORGE D. WATSON, OF TORRANCE, CALIFORNIA.

OIL-WELL TOOL.

Application filed November 16, 1925. Serial No. 69,323.

This invention relates to oil well tools, and particularly to that class of oil well tool known as a swage. Swages are used wherever pipe has collapsed, due to various causes such as a well hole caving in and bending inwardly the said pipe. The ordinary way of taking out the dents in a pipe is to use what are called swages, and which usually comprise an oval shaped tool which is run below the stem with long-stroke fishing jars immediately above the swage. The tools are run in the well hole until the swage stops upon striking the dented or collapsed portion of the pipe. The hitch is then taken off, driving or jarring down the swage. After the swage has been driven through the collapsed or dented portion of the pipe the swage is then pulled back up the pipe to further assure that the bad place is entirely ironed out. It often occurs that small swages must first be used to start the bad place after which larger swages are consecutively used until a swage of maximum diameter is easily driven through the pipe.

The present invention has for an object the provision of a swage which is easily handled and may be easily jarred past a bad place in a pipe, and which is so constituted as not to readily wedge in a bad place of the pipe. The wedging of swages in the ordinary form of swage often results in a breaking of the pin of the swage, which of course will result in serious damage to the oil well, because a swage with a broken pin is almost impossible to remove.

Another object of the invention is the provision of a swage which may be easily manufactured and which is simple of structure and generally superior.

With the above and other objects in view, the invention consists in the novel and useful provision, formation, construction, association and relative arrangement of parts, members and features, all as shown in the drawing, and finally pointed out in claims.

In the drawing:

Figure 1 is an elevation of one form of swage;

Figure 2 is an elevation of a second form of swage;

Figure 3 shows the action of the second form of swage within a bad casing;

Figure 4 is a cross sectional view on an enlarged scale, and taken on the line 4-4 of Figure 1;

Figure 5 is a cross sectional view on the

line 5-5, of Fig. 3, the casing being shown in full lines;

Figure 6 is a fragmentary enlarged plan view of the method of associating rollers with the ribs of the swage; and,

Figure 7 is a cross sectional view on the line 7-7 of Figure 6, and on an enlarged scale from the showing of Fig. 6.

Corresponding parts in all the figures are designated by the same reference characters.

Referring with particularity to the drawing, I have designated two embodiments of my invention by A and B. Generally, the constructional features of both of said embodiments are the same.

Referring to Figures 1 and 4, the swage includes a body portion *a* which is formed adjacent one end with a shank portion *1* which terminates in a tapered screw-threaded pin *2*, the opposite end of the body tapering to a point or approximately a point as shown at 3. A section of the body shows that the body is cruciform in section, forming four spaced ribs *4*, *5*, *6* and *7* extending from a central portion *8*. The ribs are in the form of a spiral helix from that zone marked *9* to the point *3*, while the portion of said ribs above the zone marked *9* is in the form of a helix. It is to be noted that the spacing between the ribs allows for circulation passages *10*. The ribs extend to the zone of a curved shoulder *11* which is joined to the shank *1*. Carried by each rib is a series of spaced anti-friction means *b*. The said anti-friction means in the present embodiment takes the form of rollers, the axis of each roller being approximately at right angles to the longitudinal axis of the body of the swage. Thus, when the swage of the form shown in Figure 1 is inserted within casing *12* which has an indented portion to be removed, there will be no tendency for the swage to twist or turn due to the spiral arrangement of the arms. The anti-friction means *b* may be conveniently inserted within the ribs by

the method shown in Figures 6 and 7, where in the rib or ribs is or are bored transversely, as shown in Figure 7 at *12*, it being noted that the bore is not a complete circle, with a roller inserted within each said bore and so that a portion of the periphery of each thereof projects from the respective bores and beyond the periphery of the rib, as shown at *13*. An end piece *14* is then placed in each bore to act as an abutment for the rollers and to prevent

the rollers from escaping from the bores 12. These pieces 14 will conform in shape to the rib, as shown in Fig. 6, and such pieces may be conveniently secured to the rib by welding or any other well known means. The inventor is aware that swages are now on the market which have a cylindrical body with rollers projecting therefrom, but in every case that he is aware of considerable difficulty is experienced in placing the rollers within the swage body. With the present method as just described, it is an easy matter for any mechanic to insert rollers in the ribs, the very construction of the swage easily permitting this to be accomplished. The swage shown in Figures 2 and 3 does not differ essentially from the form shown in Figure 1, with the exception that the said ribs 15, 16, 17 and 18 joined to the center section 19, are not spirally arranged with relation to said center section 19. Furthermore, two of the ribs 15 and 17 which are diametrically opposite, are of greater length than the ribs 16 and 18. The two ribs 15 and 17 come to a point, or approximately a point, as shown at 20, and the two ribs 16 and 18 terminate some distance above the said point 20. Each of the said ribs, as is the case of the form A carries anti-friction members *b* and which anti-friction members are secured within said ribs in the same manner as for the form A. In order to provide for circulation or relief of pressure when the swage is actually used, a bore may be made in the pin and shank of the swage with the bore having branch portions which permit communication between adjacent ribs, as shown in Figure 3 by dotted lines at 21 and 22.

The operation of the swage just described is as follows:

In Figure 3 I have shown what may be termed a bad pipe or casing C and which pipe has collapsed or become indented at the zone marked 23. It is perhaps unnecessary to state that swages are used which have a diameter but a fraction of an inch smaller than the diameter of the casing through which it must be passed, and it will be noted in the present instance that the roller members on the swage are contacting with the inner surface of the casing, as shown at 24. The ribs 15 and 17 have contacted with the restricted zone 23 of the casing and their tendency will be to wedge apart such collapsed wall of the casing prior to the ribs 16 and 18 contacting with such collapsed

portion. In other words, this swage acts to initially iron out the indented or collapsed portion of the casing. The step of forcing out the casing so that it may assume a normal configuration is gradual and not sudden, as is the case of the average swage. After the swage shown in Figs. 2 and 3 has successfully operated in the bad pipe or casing, the pipe will assume a form as appears in Figure 5, wherein it will be seen that due to the right-angled relation between the ribs the pipe is forced outwardly at adjacent ends of each rib, as shown at 25 more than the pipe is forced outwardly in zones intermediate the ribs as shown at 26. The result will be that the pipe is not round. To make the pipe round the tools are drawn up to the surface of the well and the swage of the form shown in Fig. 1 is then lowered within the casing and this swage when jarred will make the pipe perfectly round, as would be evident upon an inspection of Fig. 4, for the reason that there will be a zone of contact against the pipe at all portions of the pipe, due to the spiral formation of the ribs.

It is obvious that various minor changes and modifications may be made in practicing the invention, in departure from the particular showing of the drawing, without departing from the true spirit of the invention.

Having thus disclosed my invention, I claim and desire to secure by Letters Patent:

1. A swage formed with spaced ribs and tapering toward its forward end.
2. A swage formed with spaced ribs and tapering toward its forward end, and anti-friction means on the outer face of said ribs.
3. A swage formed with spaced spiral ribs and tapering toward its forward end.
4. A swage formed with spaced spiral ribs and tapering toward its forward end, and antifriction means on the outer face of said ribs.
5. A swage formed with ribs extending from end to end, and anti-friction rollers journaled in said ribs transversely of the axis of the swage.
6. A swage formed with spiral ribs, and anti-friction rollers journaled in said ribs transversely of the axis of the swage.
7. A swage formed with spiral ribs, and anti-friction means mounted in said ribs to facilitate jarring of the swage in a well casing.

In testimony whereof I have signed my name to this specification.

GEORGE D. WATSON.
